UNITED STATES PATENT OFFICE.

BENJAMIN G. RAND, OF NORTH TONAWANDA, NEW YORK, ASSIGNOR TO THE RAND COMPANY, OF NORTH TONAWANDA, NEW YORK, A CORPORATION OF NEW YORK.

WIRE-STITCHING MACHINE.

1,306,025.

Specification of Letters Patent. Patented June 10, 1919.

Application filed August 28, 1916. Serial No. 117,212.

To all whom it may concern:

Be it known that I, BENJAMIN G. RAND, a citizen of the United States, residing at North Tonawanda, in the county of Niagara and State of New York, have invented new and useful Improvements in Wire-Stitching Machines, of which the following is a specification.

This invention relates to improvements in 10 stapling or stitching machines, and particularly to means for guiding or gaging the articles to be stitched.

It is the object of this invention to provide means on the work-supporting table 15 which will cause the stitching mechanism of the machine to produce stitches obliquely to the edge of the article, as such stitches can be inserted with greater facility and neatness than stitches parallel with the edge of 20 an article. Parallel stitches require the use of closely-arranged parallel guides over which the articles to be stitched must lap, preventing them from lying flat on the table and producing inferior work.

25 A further object is to produce a simple and efficient device of this character which can be readily applied to and removed from the stitching machines now on the market.

In the accompanying drawings:

30 Figure 1 is a fragmentary vertical section of a stitching machine, embodying my improvements. Fig. 2 is an enlarged fragmentary top plan view of the table of the machine to which my device is applied.

35 Similar characters of reference indicate corresponding parts throughout the several views.

The stitching or fastening mechanism forms no part of my present invention and 40 may be of any suitable or well known construction, such for instance as shown and described in Letters Patent of the United States No. 662,184, issued November 20, 1900, to T. A. Briggs and T. Barrett. In 45 the drawings, only such parts are shown as are related to the improved guide.

1 indicates the fixed horizontal arm or gooseneck of the stitcher having suitable bearings in which the driving shaft 2 is 50 journaled. Arranged at the front end of this arm is the wire supply spool 3 which is loosely mounted on a spindle 4 secured to said arm. From this spool the wire passes to a suitable cutter mechanism, not shown, 55 which severs the wire to the desired length

to form the stitches or staple-blanks. Each staple blank is guided onto an anvil bar 5 which slides in a curved grooved 6 arranged in a vertically-movable presser 7. A vertically movable bending bar 8 is arranged in 60 front of the presser 7 and moves in a vertical guide bar 9. Upon the downward movement of this bending bar the legs of the staples or stitches are formed after which they are clenched by the customary clinching 65 jaws, not shown. The legs of the staple enter the usual slots or throats 10 located below the staple forming and driving devices.

Arranged adjacent to the mechanism previously described, is a horizontal table 11 which supports the articles to be stitched. A guide or gage plate 12, preferably in the form of an isosceles triangle, is secured to the top of this table by screws 13 or other 70 appropriate means, so that the opposite sides thereof converge toward the stitching mechanism. This gage plate is located centrally on the table 11 with its apex in line with the center line of the stitching mechanism, 75 so that its side edges are symmetrically disposed with reference to the latter. As shown in the drawings, the wide end of the plate overhangs the table a suitable distance to present an extensive bearing surface at 80 its opposite edges to the articles to be stitched, while the apex of the plate is definitely positioned in front of the stitching parts of the machine, so as not to interfere therewith and to permit the article being 85 90 stitched to be properly located relatively to said parts.

To limit the forward movement of the article to be stitched and properly position it preparatory to that operation, a front 95 gage or stop 14, preferably in the form of a flat spring, is fastened to the rear portion of the table 11 with its upper edge projecting normally above the surface of the table, as shown in Fig. 1. This gage is arranged in the opening 15 in the table which is necessary for the vertical movement of the presser bar 7 and associated parts of the stitcher. The gage, being made of a flat strip of metal, is resilient enough to yield 100 to the descending presser bar during the stitching operation and to return to its normal position after that operation. The gage is preferably so located that the stitches in the articles will be close to their edges, al- 110

though the gage may be made adjustable, if desired to place the stitches at a greater or less distance from the edges.

The article illustrated in the drawings, by way of example, is an index card 18 having at its lower edge a pocket or holder adapted to receive an index or memorandum slip, not shown, and formed by a folded strip 19 of celluloid stitched to the card.

10 In the use of a machine equipped with the improvement, the index card is placed flat on the table with its folded edge against one of the side gages formed by the side edges of the guide 12 and its front edge against 15 the stop 14, as shown by full lines in Fig. 2. While the card is in this position, the machine is operated to form one or more stitches 20 therein. The other end of the card is then likewise stitched by reversing 20 it end for end and placing it against the opposite edge of the guide, as shown by dotted lines in Fig. 2. In this manner oblique stitches can be made at both ends 25 of the index card or other article, which converge toward its upper end.

By the use of this improved guide the articles can be conveniently stitched at both ends in a relatively short time. The guide allows them to lie flat on the table without 30 overlapping the guide, producing neat stitches and facilitating the operation of presenting the articles to the stitching mechanism. Moreover, the guide is small and

occupies but little space on the table, leaving ample room for the hands of the operator.

I claim as my invention:

1. In a stitching machine, the combination with fastening mechanism and a table for supporting the articles to be fastened, of a triangular guide mounted on said table with its apex facing the fastening mechanism, the lateral forwardly-converging edges of said guide forming side gages symmetrically disposed with reference to the fastening mechanism, and the portions of said table on opposite sides of said guide being unobstructed to allow the article to lie flat thereon and against the side edges of the guide.

2. In a stitching machine, the combination with fastening mechanism and a table for supporting the articles to be fastened, of a front gage arranged adjacent to the surface of said table and located on the front side of the fastening mechanism, and a triangular guide mounted on said table with its apex facing said fastening mechanism and separated therefrom, leaving between the guide and the fastening mechanism an unobstructed space for the corner of the article to be fastened, the forwardly-converging edges of the guide being symmetrically disposed with relation to the fastening mechanism.

BENJAMIN G. RAND.
